[57] CLAIM

The ornamental design for an adjustable skylight, as shown and described.

DESCRIPTION

FIG. 1 is a top plan view of an adjustable skylight showing my new design;

FIG. 2 is a bottom plan view thereof;

FIG. 3 is a front elevational view thereof;

FIG. 4 is a right side elevational view, the left side being identical thereto;

FIG. 5 is an enlarged cross-sectional view taken along line 5—5 of FIG. 1, the cross-section of the adjustable light shown broken in the center to show the adjustable light in its entirety;

FIG. 6 is a front elevational view thereof with the wing frame shown open;

FIG. 7 is a right side elevational view thereof with the wing frame shown open, the left side being identical thereto; and,

FIG. 8 is a perspective view thereof, the broken line showing of a roof is for illustrative purposes only and form no part of the claimed design.
